DESIGN FOR A PEDESTAL FOR TYPE-WRITING MACHINES

Lurelle V. A. Guild, Darien, Conn., assignor to
Underwood Elliott Fisher Company, New York,
N. Y., a corporation of Delaware

Application July 29, 1942, Serial No. 107,744

Term of patent 14 years

To all whom it may concern:

Be it known that I, Lurelle V. A. Guild, a citizen of the United States of America, residing in Darien, in the county of Fairfield and State of Connecticut, have invented a new, original, and ornamental Design for a Pedestal for Typewriting Machines, of which the following is a specification, reference being had to the accompanying drawing, forming part thereof.

The figure is a perspective view of a pedestal for typewriting machines, showing my new design.

I claim:

The ornamental design for a pedestal for typewriting machines, as shown.

LURELLE V. A. GUILD.
